UNITED STATES PATENT OFFICE.

LOUIS G. PACENT, OF WINFIELD, NEW YORK.

COMBINATION JACK AND LIGHTNING ARRESTER.

Application filed May 23, 1923. Serial No. 640,825.

To all whom it may concern:

Be it known that I, LOUIS G. PACENT, a citizen of the United States, residing at Winfield, in the county of Queens, State of New York, have invented certain new and useful Improvements in Combination Jacks and Lightning Arresters; and I do hereby declare the following to be a full, clear, and exact description of the invention; such as will enable others skilled in the art to which it appertains to make and use the same.

This invention relates to electrical protection devices, and, more particularly, lightning and static discharge arresters for use in conjunction with radio antenna systems and the like.

The invention has for its object the provision of a unitary structure in which is combined a pair of connector terminals for antenna and ground connections, respectively, and a spark gap device connected between the terminals together with means for quickly connecting and disconnecting the radio apparatus to and from the antenna and ground. The last-mentioned means is preferably in the form of a spring jack designed to receive a plug of the telephone type.

According to the preferred embodiment of the invention, the spark gap device and spring jack are mounted in a receptacle forming a part of a supporting member on which the connector terminals, such as binding posts, are mounted. The supporting member in the preferred embodiment is molded of a suitable insulating material, such as bakelite, and designed to be mounted in an aperture in a wall or panel or other medium. The spark gap device consists, preferably, of an evacuated glass container enclosing a pair of gap terminals, and is removably mounted inside the receptacle and held in place by a contact spring. The spring jack in this preferred embodiment is in the form of a cap which functions as a closure for the receptacle and which may be easily removed for gaining access to the interior of the receptacle.

A clearer understanding of the invention may be had from the detailed description which follows in conjunction with the accompanying drawing. Referring to the drawing,

Fig. 1 is a perspective view of the preferred embodiment of the invention;

Fig. 2 is a longitudinal section through the structure shown in Fig. 1;

Fig. 3 is a cross sectional view taken along the line 3—3 of Fig. 2;

Fig. 4 is a cross sectional view of an alternative embodiment of the invention; 60

Fig. 5 is a cross sectional view taken along the line 5—5 of Fig. 4; and

Fig. 6 is a front elevational view of the structure shown in Figs. 4 and 5.

The device illustrated in Figs. 1, 2 and 3 comprises a supporting member 1 which is preferably molded of a suitable insulating material as, for instance, bakelite. The supporting member is in general of cylindrical form and is provided with a cylindrical chamber 2 adapted to receive a spark gap device 4 consisting of a glass tube 5 closed at its ends by metal caps 6, to each of which is attached a gap terminal 7. The gap between the terminals 7 is of suitable length 75 to permit lightning and dangerous static discharges accumulating in the antenna to jump across and thence pass to ground. The spark gap device is preferably highly evacuated in order to lower the resistance of the 80 gap. This device fits loosely in the chamber 2 and is held in place, as shown, by means of a contact spring 8, which is connected to the rod 9, the end of which is provided with a pair of nuts 10 between which a ground 85 conductor 11 may be connected. The end of the spark gap device opposite the contact spring 8 is electrically connected to the rod 12 through the medium of a metallic link 13 through which the rod 12 passes and with 90 which it contacts. One end of rod 12 is provided with a pair of nuts 14 between which the antenna conductor 15 is connected. An insulating rubber shield 16 may be applied over the end of the antenna 95 terminal as illustrated in Fig. 2. The function of this shield is to keep the otherwise bare connections protected against moisture, thus tending to reduce surface leakage. The corrugated extension 1^a is provided in order 100 to increase the surface distance between the antenna and ground terminals for the purpose of decreasing the surface leakage between these terminals, particularly in wet weather. The supporting member 1 is 105 shown mounted on a panel 17, which may be an ordinary switchboard panel or it may be, for instance, a brick wall. The length of that portion of the supporting member 1 which extends through the panel 17 or wall 110 or whatever medium the device may be mounted upon is proportioned to suit the

thickness of such medium. The supporting member is provided with an external thread 18 which is engaged by a large nut 19, the function of which is to securely retain the device on its mounting. A pair of lead gaskets 20 may be provided for securing a waterproof joint.

The chamber 2 is enclosed by a cap 21, which is preferably molded of the same material as the supporting member 1 and is provided at its center with an aperture 22 of proper size to receive a connector plug of the telephone type 23, as illustrated. Contact springs 24 and 25 are designed to cooperate with the plug 23 and are mounted on the rods 9 and 12 respectively, with which they make contact. The contact springs 24 and 25 are accordingly connected respectively to the ground and antenna terminals.

As an alternative means for connecting radio apparatus to the device, knurled binding nuts 26 are provided which are connected respectively to the rods 9 and 12. This is a convenient provision in cases where a connector plug may not be available.

It will be noted that the spark gap device 4 and the jack springs 24 and 25 are connected in parallel between the antenna and ground terminals.

The alternative arrangement illustrated in Figs. 4, 5 and 6 is particularly convenient for use where it is undesirable to bore a hole of considerable size through the wall of a building. This device comprises a molded supporting member 27 in the form of a receptacle in which the spark gap device 4 is mounted by means of spring clips 28 and 29. Spring clips 28, of which there are two, are connected respectively to the screws 30, which function as antenna and ground terminals. The screws 30 are provided with nuts 31, by which they are held in place, and wing nuts 32. The antenna and ground conductors are connected between the nuts 31 and 32, as illustrated in Fig. 4. As will be seen, the spark gap device is so con-

nected that the gap is between the antenna and ground terminals. The spring clips 29 are provided with extending portions 29a, 50 which connect respectively with jack contact springs 33 and 34, as is most clearly shown in Fig. 5. The supporting member 27 is provided with an aperture 35 of suitable size to permit the insertion there-through of the contact portion of the connector plug 36, the tip and sleeve of which connect respectively with the jack contact springs 34 and 33. As shown in Fig. 4, the axis of aperture 35 is disposed at a convenient angle for plugging in. The supporting member 27 is provided with three mounting screw apertures by which the device may be mounted on a wall or panel.

I claim:

1. In combination, a supporting member comprising a receptacle, a portion of said supporting member being cylindrical in form and threaded on its exterior, said cylindrical portion being adapted to be inserted through an aperture in a wall or the like and a nut for engaging the threaded cylindrical portion for securing the supporting member, a spring jack mounted in said receptacle, said spring jack being operatively accessible for plugging in from the exterior of said receptacle, a spark gap device disposed within said receptacle, and a pair of connector terminals mounted on said supporting member, said jack and said spark gap device being connected in parallel between said terminals.

2. In combination, a supporting member comprising a receptacle, a pair of connector terminals on said supporting member, a spark gap device removably mounted in said receptacle, a cap for enclosing said receptacle, and a spring jack carried by said cap, said spark gap device and said spring jack being connected in parallel between said terminals.

In testimony whereof I affix my signature.

LOUIS G. PACENT.
